UNITED STATES PATENT OFFICE.

GEORGE BALDWIN, OF DELL, MONTANA, ASSIGNOR OF ONE-THIRD TO EDWARD DRESCHER, OF DELL, MONTANA.

BORING-MACHINE.

1,331,949.

Specification of Letters Patent. Patented Feb. 24, 1920.

Application filed April 27, 1917. Serial No. 164,939.

To all whom it may concern:

Be it known that I, GEORGE BALDWIN, a citizen of the United States, residing at Dell, in the county of Beaverhead and State 5 of Montana, have invented certain new and useful Improvements in Boring-Machines; and I do hereby declare the following to be a full, clear, and exact description of the invention, such as will enable others skilled 10 in the art to which it appertains to make and use the same.

This invention relates to new and useful improvements in boring machines, and the principal object of the invention resides in 15 the provision of a device which is particularly adapted for wood boring and on which the drill is slidably mounted in order that the same may be adjusted to bore through various thicknesses.

20 Another object of the invention is to provide a device in which the drill is mounted on a vertically sliding carriage which is suspended yieldably on suitable spring suspending elements which are adapted to be 25 adjusted so that the tension of the springs may be varied to meet varying requirements.

A still further object of the invention resides in the provision of a novel means for 30 holding the drill bit in place on the drive gear.

With these and other objects in view, the invention consists in the novel combination and arrangement of parts which will be 35 fully set forth in the following specification and accompanying drawings, in which:

Figure 1 is a side view partly in section illustrating the detailed construction of the 40 drill or boring machine;

Fig. 2 is a top plan view of the device; Fig. 3 is a sectional view on line 3—3 of 45 Fig. 1;

Fig. 4 is an enlarged detailed sectional view through one of the springs showing the 50 method of adjustment;

Fig. 5 is an enlarged sectional view through the chuck; and

Fig. 6 is an enlarged detailed view of the 55 supporting plug fitted in the upper end of the standard.

Referring to the drawings, 1 designates the base of the device, consisting of a plate having one edge provided with a binding strip 2. This binding strip is provided in- 60

flanges 4 formed thereon which are secured to the plate as illustrated in the drawings. A standard 5 is secured in said socket and extends upwardly from the base at right angles thereto as will be clearly seen upon reference to the drawings. A guide comprising a pair of spaced bars 6 is secured to the base in the rear of the standard 5 and the upper ends of said bars are provided with forwardly extending arms 7 which are provided at their forward ends with a loop 8. This loop 8 surrounds the standard 5 adjacent its upper end as will be clearly seen upon reference to Fig. 1, and serves to brace 65 said standard.

Seated in the upper end of the standard is a plug 10 provided with a transverse bore 11 for the reception of a suitable bolt or rivet by means of which the plug is secured in place. A plurality of arms 12 are on the 70 upper end of the plug and are provided adjacent their upper ends with apertures 13 for the reception of the pivot pin of the adjusting lever and spring connector which will be more fully hereinafter described. One of the vertically extending arms is 75 provided with a segment 14 having ratchet teeth for coöperation with a suitable latch mechanism 15 carried by the lever by which the various adjustments are made.

80 Pivoted between one pair of arms of the plug on a suitable pivot pin 16 is a lever 17 provided with the latch mechanism 15 for coöperation with the teeth of the segment 14 and this lever has secured to its end a connecting rod 18 to which is connected an adjustable rod 19 the lower end of which is bifurcated and attached to a suitable ear formed on the carriage as will be more fully 85 hereinafter described.

90 The carriage above referred to is designated generically by the numeral 20 and comprises a vertical tube 21 having formed thereon a bow-shaped frame 22. The transversely extending horizontal tube 23 is 100 formed integrally with the vertical tube and a similar tube or bearing 24 is formed on the right portion of the bow 22 and aligns with the tube 23 for the reception of the drive shaft which will be more fully 105 hereinafter described. Journaled in the bearings or tubes 23 and 24 is a drive shaft 25 having attached thereto a hand wheel 26 while the opposite end of said shaft carries a beveled gear 27 for meshing engagement 110.

with the beveled gear of the chuck which will be more fully hereinafter described. Formed at the lower end of the tube 21 of the frame 20 is an arm 28 provided with an aperture 29 in which the chuck and rotating pinion therefor, is mounted. A suitable ear 30 is formed on the tube 24 while a similar ear 31 is formed on the tube 23. The ears 30 and 31 however, extend in planes at right angles to each other and extend outwardly from their tubes so that their axes are positioned at right angles with relation to each other. The lower end of the adjustable rod 19 is connected to the ear 31 as clearly illustrated in Fig. 1. It will thus be seen that by the manipulation of the lever 17, the carriage may be vertically adjusted on the standard.

Formed on the tube 21 of the carriage, 20 are suitable outstanding ears between which are rotatably mounted the rollers 32, which extend through slots in the tube 21 and engage the standard to allow for free vertical movement thereof.

25 Rotatably mounted within the bore 29 in the arm 28, is a hub 34 of a pinion 35 which meshes with the gear 27 previously referred to. This pinion has secured to its underside a plate 36 and the plate and body of the 30 pinion form a groove in which the walls of the opening 29 are seated. A tapered bore 37 extends through the pinion 35 and hub 34 and fitted in said bore is a chuck 38 comprising a pair of arms 39 having the jaw members 40 formed at their lower ends. The upper ends of the arms are connected by the apertured bight portion 41 through which a bolt 42 extends beyond the upper face of the pinion 35 and is provided with a 35 wing nut 43 by means of which the various degrees of tightness may be had. The jaw members 40 are adapted to receive the shank of the drill 44 and it will thus be seen that when the drive wheel 26 is rotated, the shaft 45 25 will rotate the gear 27 driving the pinion 35 and causing the chuck 38 to revolve, thereby rotating the drill bit.

In order to yieldably force the carriage 20 downwardly into the work, a spring 50 structure designated generically by the numeral 45 is provided and has one end connected by means of a rod 46 to a bracket 47 secured to the upper horizontal arms 7 of the rods 6. The lower end of the spring 55 structure is connected in any suitable manner to the ear 30 and it will thus be seen that the rear end of the carriage will be yieldably forced downwardly toward the walls. The forward end of said carriage is forced downwardly by a spring structure designated by the numeral 45^a which is constructed in a manner similar to the spring structure above mentioned.

The spring structures 45 and 45^a hereinbefore referred to are best illustrated in Fig.

4 and each comprises a plate 46 having a pair of arms 47 extending from one face thereof. These arms are arranged at diametrically opposite points and extend in spaced parallel relation to each other and are provided with gear teeth 48 the use of which will appear as the description proceeds. A similar plate 49 is provided and is formed at diametrically opposite points with notches 50 for the reception of the 70 arms 47 and formed on the plate are yokes 51 through which thumb screws 52 are threaded which screws have swivelly connected to their inner ends suitable gear wheels 53 which mesh with the teeth 48 on 75 the bars 47 and assist in holding the plates 46 and 49 in spaced relation.

Supported on the pivot pin 16 between the standards 12 opposite those in which the lever is pivoted is a block 54 provided with a depending off-set extension 55 having a roughened face 56 and a slot 57. A plate 58 provided with a roughened face is slotted in a similar manner as the extension 55 and a bolt 59 passes through the slots and holds 90 the plate in various adjusted positions on the extension. The lower end of the plate extends downwardly and is provided with a connection by which it is attached to the feed spring 45^a. A loop 60 is pivotally connected to the handle of the lever 17 and serves to hold the pawl out of the segment 95 when the device is in operation.

It will be apparent from the foregoing, 100 that in use the handle of the lever is pulled downwardly thereby rocking the same on its pivot so as to raise the carriage 20 and move the drill 44 and the operating mechanism thereof upwardly. The work is then placed beneath the drill and the pawl carried by the lever is released to allow the handle of the lever to move upwardly and the carriage downwardly until the drill engages the work after which the loop 60 is attached to the hand grip so as to hold the 105 pawl out of contact with the segment and the hand wheel 26 is then turned thus setting the drill in operation. The feed springs 45 and 45^a will force the carriage downwardly and simultaneously force the drill 110 into the work and the speed of movement of the carriage is varied by adjustment of the thumb screws of the feed springs.

It will be understood that should it be 115 so desired, a belt which may be connected to any suitable driving means may be passed around the hand wheel 26 or a pulley may be substituted in lieu of the hand wheel without departing from the spirit and scope of this invention to enable the device to be 120 power operated.

While in the foregoing there has been 125 shown and described the preferred embodiment of this invention, it is to be understood that such changes may be made in the 130

combination and arrangement of part as will fall within the spirit and scope of the appended claims.

What is claimed is:

- 5 1. A device of the character described comprising a base, a standard extending vertically from said base, a brace for said standard extending vertically from the base, a frame slidably mounted upon the stand-
ard and extending in operative relation to the brace, brackets connected with the standard and brace, spring elements positioned between the brackets and frame for normally holding the frame in a lowered position, each of the spring elements comprising a base connected with the frame, arms extending from the base and provided with teeth forming rack bars of said arms, a yoke connected with the brackets and having openings through which said arms pass, a spring positioned between the arms and having its upper end engaging the yoke and its lower end engaging the base threaded stems extending through threaded openings formed in the yoke, and pinions rotatably carried by the inner end portions of the stems and engaging the teeth of said arms and constituting brake elements, drill carrying means carried by the frame for rotary
- 10 movement, and actuating means carried by the frame for imparting rotary movement to the drill carrying means.
- 15 2. A device of the character described comprising a slidably mounted frame, drill carrying means rotatably carried by the frame, actuating means carried by the frame for imparting rotary movement to the drill carrying means, and resilient means for normally retaining the drill carrying frame in a lowered position and comprising a stationary support, a yoke carried by the support and having side housings, a base connected with the slidably mounted frame, rack bars extending from the base and ex-
tending through openings formed in the yoke between the side housings, a spring ele-
ment positioned between the rack bars and engaging the yoke and base, threaded stems carried by the side housings, and pinions ro-
tatably carried by the stems and engaging the teeth of the rack bars constituting brake elements.
- 20 In testimony whereof I affix my signature in presence of two witnesses.
- 25 GEORGE BALDWIN.
